UNITED STATES PATENT OFFICE

OSWALD BERGER-STALDER, OF BERN, SWITZERLAND

WATERPROOF JOINT FOR TRUNK LIDS AND THE LIKE

Application filed November 18, 1926, Serial No. 149,213, and in Switzerland and Germany March 8, 1926.

The present invention relates to a waterproof joint for trunk lids and consists in a peculiar arrangement made at the meeting of the edges of lid and trunk body in order 5 to insure a perfect water tightness of the joint.

In the accompanying drawing one form of the invention is shown, in which:—

Fig. 1 is a fragmentary transverse sectional 10 view showing the joint in open position, and Fig. 2 is a similar view showing the joint in a closed position.

According to the drawing the lid D of the trunk C has a border C¹ provided with 15 a tongue-like edge D¹ which may have a velvet lining (not shown).

This tongue-like edge D¹ fits into a U-shaped groove A formed by a frame F which is fixed to the edge of the trunk by means 20 of a downwardly extended inner leg F¹ while a pocket B is integral with the outer leg of the U-frame and projects over the outside of the edge of the trunk body and is slanted outwardly by means of an elastic packing 25 strip N inserted between the trunk body and the pocket B. The water-tight connection between the trunk body and the frame is insured by means of a resilient lining K provided on the top edge and the upper part of 30 the inner face of the trunk body. The water-tight joint comprises first a metal shield E which is attached to the outside of the border C¹ and is extended downwardly into said pocket B and secondly a water-tight covering 35 E¹ surrounding said lid and the extended portion of said shield. In order to have the pocket B filled up tightly a resilient packing strip H is attached to the outer face of the shield and adjacent the lower edge thereof 40 and likewise enclosed by the covering E¹.

Having thus fully described the invention what is claimed as new and desired to be secured by Letters Patent is:

A waterproof joint for trunks and the 45 like including in combination, a trunk body, a lid, a tongue on the lower edge of the lid, a metal frame U-shaped in cross section forming a U-groove adapted to receive said tongue and fixed to the upper edge of the trunk body 50 and including downwardly extending inner

and outer legs, a resilient water-tight lining between the upper edge of the trunk and the frame and a pocket carried by the outer leg of said U-frame and projecting over the edge of the trunk body, an elastic wedging strip 55 inserted between trunk body and the pocket and slanting said pocket outwardly, a sheet metal shield attached to the outer surface of the lid edge for engagement with said pocket, a resilient packing strip attached to the outer 60 face and adjacent the lower edge of the shield and a watertight covering surrounding said lid and shield together with the said packing strip.

In testimony whereof I affix my signature. 65
OSWALD BERGER-STALDER.
